STEEL DAM

Jaroslav Fultner, Gregory Gregorjevitch Krivoshein, and Josef Sekla, Prague, Czechoslovakia

Application August 24, 1934, Serial No. 741,310
In Czechoslovakia November 11, 1932

2 Claims. (Cl. 61—32)

Dam constructions which have hitherto been constructed whether submerged or not submerged or a combination of the two types have usually been made of filled-in earth, filled-in stone, rammed or cast concrete or of reinforced concrete. For building dams steel has also been used, but these dams have not been satisfactory on account of defects in their construction although the steel material, more particularly non-rusting or corrosion resisting steel is the most suitable material for such constructions.

Other proposals which have been made for steel dams have not been successful on account of their high costs which the very complicated steel constructions entailed. The construction according to the invention is simply and rationally constructed. In addition to economical reasons, reasons of safety make it advisable to build steel dams. The curved construction of a dam according to the invention is completely watertight and elastic, allows of expansion without joints and also, in case of a catastrophe, a breaking of a steel wall, in view of the articulated construction thereof, cannot cause very extensive damage in the land below the dam.

In order to obtain all the above-mentioned advantages of steel dams and to avoid the various disadvantages of hitherto unsuccessful steel dams, according to the present invention the construction of a steel dam is solved in a particularly advantageous manner. The curved steel dam according to the invention forms a combined dam wall which consists of a series of inclined convex cylindrical surfaces of corrosion-resisting steel plates of great span which are reinforced with ribs of section steel. The wall constructed in this manner rests without any transverse girders on oblique longitudinal girders which are supported by struts which are practically at right angles thereto. The separate cylindrical convex surfaces according to the invention act in the manner of a boiler wall. The use of arched walls of great span without any transverse girders and the expansion of the arches made possible in this manner constitute an essential distinction between the invention and the hitherto known steel dams, which consist of a structure of transverse and longitudinal girders covered with plates and the like.

In addition to the small weight the construction according to the invention gives the result that a change in temperature cannot produce any transverse extension or contraction of the dam. A change in temperature results simply in a change in the radius of curvature of the individu-

al cylindrical segments. By the construction according to the invention the detrimental influence of the temperature and the necessity of providing expansion joints, such as are necessary in concrete, reinforced concrete or other steel dams, is completely avoided.

A further improvement of the curved steel dam according to the invention consists in the use of rigid abutment bodies which are constructed on the air side of the dam and against which the dam wall is supported either directly or by means of oblique struts, the dam according to the invention when constructed in this way having, in cross section, substantially the shape of a right angled triangle. The important technical effect obtained in this way consists in a considerable shortening of the dam breadth at its base.

The abutment member may be constructed in different ways; either using vertical columns fixed in the ground or resting with their ends at a foundation, the columns supporting the upper oblique struts or by means of abutment members which preferably have the form of a right-angled triangle, against the hypotenuse of which the dam member bears either directly or through oblique struts, preferably at right angles to the hypotenuse.

The invention is illustrated by way of examples in the accompanying drawing.

Figures 1, 2 and 3 show in a vertical section a plan view, and a back view a dam which is normally not submerged.

Figs. 4 and 5 are vertical sectional views of two further modifications of the arrangement shown in Fig. 1.

Fig. 6 is an enlarged fragmentary plan detail partly in section of a modified surface of the dam, and

Fig. 7 is a schematic sectional detail view.

Referring more particularly to Figs. 1, 2 and 3 the dam is composed of a series of inclined cylindrical surfaces 1 supported on longitudinal girders 2. The girders 2 are supported by oblique struts 3 which rest on foundation blocks 4. The individual blocks 4 may be connected together by tension rods placed at right angles to the direction of the dam.

Figure 1 shows a dam with a system of triangular abutment members 15 against the hypotenuses of which the dam members bear directly. The abutment members are formed by a rigid system of intersecting struts 3 and struts 16, which latter run parallel to the longitudinal girders 2.

The outer points of intersection of the struts 3 and 16 are connected together by vertical or

oblique rods 17 and the points of intersection lying in the line of the foundation bear against the foundations 4. Fig. 4 shows a similar system. The systems of construction according to Figures 1 and 4 are shown as stable and statically determined constructions.

Figure 5 shows a dam with abutment members 15 which are constructed on the air side of the dam in the form of vertical arched columnar supports, against which the dam wall 1 resting on the girders 2 bears through the upper oblique struts 3, while the lower struts rest directly on the foundations 4.

The various systems described are stable and may be constructed as statically determined or not statically determined. Each pair of struts 3 may be connected by a framework 6 (Fig. 3) of ordinary construction, in order to strengthen it against yielding.

The framework for connecting the struts 3 or the reinforcement against wind by means of rods 6 according to Figure 3 is carried out in the supporting construction of struts according to the invention in every other space and connects a pair of struts.

Figure 6 shows a form of the cylindrical surface of the dam. The arches may be provided with an asphalt or other protecting layer 8.

Figure 7 shows a cylindrical plate reinforced by ribs 7 of different kinds of section steel.

The steel dam construction according to the invention can be carried out by using known technical means, either riveted or welded or riveted and welded. The whole dam construction can be made ready in the workshop and the finished parts carried to the building place, which then are either riveted or welded together.

An advantage of the steel dams resides in the

fact that they can be assembled without considering the weather conditions in different seasons, and that the time for finishing the construction is considerably shorter than with other systems. A further advantage of the steel dam is a lighter and tighter connection for outlet pipe conduits and closing members, and further the attachment of inlet pipe conduits for turbines to the dam wall at the water side. The exposed and accessible pipe conduits can be looked after. Finally, machine housings of hydro-electric works can be included in the construction of the dam body. When the dam is not submerged lateral overflows can be constructed either in steel construction or of reinforced concrete.

We claim:

1. In a steel dam, an inclined dam wall including a plurality of arcuate wall members arranged side by side, substantially triangular and rigid abutments arranged on the air side of said wall members and each including a longitudinal girder member forming the hypotenuse side of the triangular abutment and engaging and supporting the marginal edges of each adjacent wall member, and strut members connected with the longitudinal girder members and anchored relative to the ground and positioned in the vertical plane of the girder members.

2. In a steel dam as claimed in claim 1, in which the strut members comprise inclined struts perpendicular to the girder members, and other inclined struts parallel to the girder members and intersecting the first mentioned struts so as to form the rigid abutments.
